MACHINE FOR APPLYING SCREW CLOSURES
TO CONTAINERSArthur Clarence Everett, Boston, Mass., assignor
to Pneumatic Scale Corporation, Limited,
Quincy, Mass., a corporation of Massachusetts

Application March 14, 1934, Serial No. 715,503

2 Claims. (Cl. 226—88)

This invention relates to a machine for applying screw closures to containers.

The invention has for an object to provide a novel and improved machine of the character specified which is relatively simple in construction, may be economically manufactured, and which functions to apply screw closures to containers in a rapid, economical and practical manner.

With this general object in view, the invention consists in a machine for applying screw closures to containers and in the various structures, arrangements and combinations of parts herein-after described and particularly defined in the claims at the end of this specification.

In the drawings illustrating the preferred embodiment of the invention, Fig. 1 is a front elevation of the machine; Fig. 2 is a side elevation of the machine viewed from the right of Fig. 1; Fig. 3 is a vertical section taken on the line 3—3 of Fig. 1; Fig. 4 is a plan view illustrating the driving mechanism and associated parts; Fig. 5 is a section taken on the line 5—5 of Fig. 1; Fig. 6 is a sectional detail taken on the line 6—6 of Fig. 1; Fig. 7 is a section on the line 7—7 of Fig. 1; Fig. 8 is a detail partly in section and partly in elevation illustrating the container stop and closure release mechanism, as will be described; and Fig. 9 is a sectional view of the closure applying chuck and associated parts.

In general, the invention is illustrated as embodied in a machine for applying screw caps to bottles, wherein the bottles are fed into the machine on an incoming conveyor 10 comprising a double set of chains, one of which is shown at 12, arranged to run around suitable sprockets 13, 14, and a pair of driving sprockets 15 mounted upon a short shaft 17 journaled in suitable bearings in the base 18 of the machine. The shaft 17 is arranged to be driven from a driving motor 20 through connections including a belt 22, cross shaft 24, having a worm 25 thereon, arranged to cooperate with a worm wheel 27 formed as a part of a sleeve 30, having a hub 32 keyed to a vertical shaft 34. The vertical shaft 34 is provided with a threaded end 35 having a nut 36 by which the shaft is supported upon the hub 32, and the latter is rotatably supported upon a thrust bearing 38 supported by a bearing 40 forming a part of the upper section 42 of the machine frame. The upper section 42 of the machine frame is adjustably mounted, as will be described, upon the base 18 of the frame, and with this construction and through the connections described, the vertical shaft 34 is arranged to be continuously rotated.

The shaft 34 near its lower end is provided with a beveled gear 44 slidably keyed thereto and arranged to cooperate with a beveled gear 46 bolted to a flange on the shaft 17, so that the driving sprockets 15 are arranged to be driven continuously during the operation of the machine, and consequently the incoming and outgoing conveyor 10 is continuously driven. The metal belt conveyor 10 offers minimum resistance to the slipping with relation to the container being gripped, as will be described, during the application of a closure thereto.

In the present machine provision is made for continuously rotating a closure applying chuck 50 and also for lowering the chuck into position 15 to engage a cap and apply the same to the container, and as best illustrated in Fig. 3 the machine is provided with a stationary housing 52 formed as a part of the upper section of the frame of the machine and within which a sleeve-like chuck carrying housing 54 is slidably mounted. The chuck carrying housing 54 is provided upon its upper end with an elongated pinion 56 with which an actuating gear 58 is arranged to mesh, the housing 52 being provided with an opening therein to permit the gear to mesh with the pinion. The chuck carrying housing 54 is provided with a laterally extended stud 60 arranged to project through a vertical slot 62 in the outer housing 52 and upon which a cam roller 64 is mounted. The cam roller 64 is received within a cam path 66 in a barrel cam 68 bolted to the gear 58, and the latter is keyed as illustrated to the vertical shaft 34, so that during the continuous rotation of the shaft 34 the chuck carrying housing 54 is lowered and subsequently raised by the revolution of the barrel cam 68 and the two high points of cam path 66.

In order to operate the chuck to open and close the same for the purpose of gripping a closure, 40 the machine is provided with a cam 70 secured to and rotatable with the hub 32. The cam 70 cooperates with a cam roll 72 on the upper end of a plunger rod 74 slidably mounted in a bearing 76 fixed to the machine frame. The lower end of 45 the plunger rod 74 is arranged to raise and lower a spindle 80 having a conical end portion 82 for the purpose of effecting the opening and closing of the gripping jaws of the chuck, and as herein shown the conical end portion 82 cooperates with 50 one arm 84 of a plurality of gripping levers 86 pivotally mounted in a driving spindle 88 on pins 90. The second arms 92 of the gripping levers 86 bear against a plurality of gripping members 94 yieldably mounted at the lower end of the 55

driving spindle 88. As a result, when the conical end 82 of the spindle is raised and lowered, the gripping jaws will be closed and opened, a suitable enclosed spring 95 tending to urge the gripping members outwardly. As herein shown, a yieldable connection is provided between the closure applying unit 50 and the plunger rod 74 including a compression spring 81 adjustably retained between collars 83, 85, the upper of which 10 is secured by a nut 87 to the spindle 80.

In order to rotate the driving spindle 88 and consequently the gripping members 94, driving connections are provided including a friction clutch indicated generally at 96. One member 98 of the friction clutch is provided with projections 97 which extend into slots 100 in the housing 54, so that as the housing 54 is rotated through the gears 56, 58, the chuck will be caused to rotate through the friction connections. The 15 friction between the members of the friction clutch may be adjustably controlled by the coil spring 89 and adjusting nut 91, as will be clearly apparent from inspection of Fig. 9. While the preferred form of closure applying mechanism 20 has been herein illustrated and described, it is to be understood that the invention does not reside in the closure applying mechanism per se and that any suitable form of closure applying chuck 25 may be used if found advantageous.

30 Provision is made for clamping and holding a container on the conveyor in vertical alignment with the closure applying chuck and for this purpose an inner clamping lever 102 and an outer clamping lever 104 are provided. As best shown 35 in Figs. 3 and 7, the inner clamping lever 102 is keyed to the upper end of a vertical rock shaft 106 which is pivotally mounted in a bearing 108 in the base 18 of the machine frame. The lower end of the shaft 106 has secured thereto a cam 40 lever 110 which carries a cam roll 112. The cam roll 112 cooperates with a cam 114 secured to a disc 116 keyed to the vertical rotating shaft 34. A spring 118 holds the cam roll 112 against the cam 114. The outer clamping lever 104 is keyed 45 to the upper end of a second vertical rock shaft 120 which is mounted in a bearing 122 in the machine frame 18. A lever 124 secured to the lower end of the vertical rock shaft 120 is connected to a cam lever 126 by a yieldable link 128. 50 The cam lever 126 is pivotally secured by a nut 131 to a stud 130 fixed in the machine frame. A cam roll 132 carried by the cam lever 126 is yieldingly urged into contact with a cam 134 by a spring 137. The cam 134 is secured to a cam disc 55 136 which is also keyed to the vertical rotating shaft 34.

The clamping levers 102 and 104 are provided with clamping members 140 and 142 which are preferably faced with soft rubber or other resilient material to prevent any injury to the containers clamped therebetween. The outer clamping member 142 is provided with an extension 144 for the purpose of engaging the forward end of the container to retain it in proper alignment with the closure applying chuck 50. From the above description it will be apparent that as the shaft 34 revolves, the clamping members will be alternately urged toward each other, to clamp and hold the container, and, away from each other to release the container and allow it to continue along the continuously moving conveyor chain 10. The yieldable link 128 includes a connection 129 secured to the cam lever 126. One end of the link 128 is loosely fitted into a hole 133 in the connection 129. A compression spring 135

is fitted between the connection 129 and a nut 138 on the end of the link 128. The yieldable connection serves to assist in retaining a firm grip on the container without danger of crushing the same after the cam 134 has reached the end 5 of its stroke.

It will be observed by reference to Fig. 7 that the container is held in a slightly angular position in relation to the conveyor. The purpose of this is to allow the container coming in on the 10 conveyor to be first engaged by the soft rubber facing of the clamping member 142 and thereby slow down gradually until it comes in contact with the metal extension 144 of the clamping member 142. This precludes the possibility of 15 any sudden stopping or jarring effect which might cause some of the contents to be spilled, more especially with a wide mouthed container.

Provision is made for feeding the closures from a bulk supply in a hopper 150 to the closure 20 applying chuck 50 and for this purpose the closure feeding device 151 forming the subject matter of the United States patent to R. N. Doble, 1,801,728 is preferably employed. In general, this feeding device comprises a rotating disc 152 25 through which is extended a plurality of closure engaging pins 154 arranged to carry the closures to a chute or closure conveyor 156, all as fully set forth in said Doble Patent No. 1,801,728, to which reference may be made. The cap feeding unit 30 151 is supported by a bracket 158 which is secured to the upper section 42 of the machine frame. The rotating disc 152 is arranged to be driven from the capping machine through a belt 160 which runs over a pulley 162 mounted on the 35 shaft 24 and a pulley 164 mounted on one end of a shaft 165. The shaft 165 is suitably mounted in a bearing 166 in the upper section 42 of the machine frame, and in bearings 168 and 170 in the closure feeding unit 151. A worm 172 fixed 40 to the shaft 165 meshes with a worm wheel 174 fast on one end of a shaft 176. The rotating disc 152 is securely attached to the second end of the shaft 176.

Provision is made for transferring the closures 45 from the closure feeding chute 156 to the closure applying chuck 50 and for this purpose a transferring arm 180 is provided. The transfer arm 180 is pivoted on a stud 182 secured to a hub 181 by a set screw 183. The hub 181 is formed 50 in a bracket 185 which is secured to the upper section of the machine frame 42. The arm 180 is supported on the stud 182 between two collars 184 and 186. The arm 180 is caused to rock from a position under the closure feeding chute 55 156 as shown in Fig. 6 to a position directly under the closure applying chuck by a cam 188 mounted on top of and secured to the cam 10. A vertical shaft 190 mounted in suitable bearings 192 and 194 in the upper section of the machine frame 42 carries a cam lever 196 at its upper end. A cam roll 198 attached to the end of the cam lever 196 cooperates with the cam 188. The lower end of the vertical shaft 190 has secured thereto an adjustable lever 200 which is 60 connected to a second arm 202 of the transfer arm 180 by a link 204. A spring 206 attached at one end to an arm 208 of the adjustable lever 200 and at the other end to a stationary part of the machine frame serves to hold the cam roll 198 65 against its cam 188.

The closures are permitted to slide down the chute 156 by gravity to a releasing mechanism, to be described, and as they are released one at a time they are stopped in their descent by a 70 75

protuberance 210 on the transfer arm 180 as shown in Fig. 8. The transfer arm 180 at this time is in its extreme backward position under the chute 156 and as it starts its forward motion, a button 212 fixed to the transfer arm 180 enters the protruding edge of the closure and as the arm 180 continues in its forward motion the closure is stripped from the chute 156 and settles down over the button 212 as shown in Fig. 6. In its travel from the chute to the closure applying chuck the closure is held from disengagement with the button 212 by a guard plate 214, fixed to an arm 216 which is attached to the stud 182. On certain types of closures it is preferable to use additional means to assist in retaining the closures in contact with the button 212 in its travel from the chute 156 to the chuck 50 and for this purpose a suction device is provided. A hole 220 in the button 212 provides an inlet or suction nozzle to retain the cap on the button 212. The hole 220 is connected to a suction pump 222 by a rubber hose 224 which is connected directly to the suction pump 222 at one end and to a hollow hub 226 of the arm 180 at the other end. A passageway 228 in the arm 180 between the hole 220 and the hollow hub 226 completes the suction line. The suction pump 222 comprises a cylinder 230, a piston 232 and a flap valve 234 hinged to the end of the cylinder 230. A link 236 connects the piston 232 to the actuating lever 208 above referred to. With this construction it will be seen that suction can be maintained during the forward stroke of the transfer arm 180. During the backward stroke the air is exhausted through the flap valve 234.

In order to release the containers on the conveyor one at a time and in timed relation to the operation of the closure applying device a stop finger 240 is provided. The stop finger 240 is adjustably mounted on a lever 242 clamped to a rocker shaft 244. The rocker shaft 244 is actuated by a barrel cam 246 attached to a disc 248 which is slidably keyed to the vertical shaft 34. A two-armed cam lever 250 pivoted on a stud 252 carries a cam roll 254 at one end and the cam roll is caused to maintain contact with the cam 246 by a spring 256. The other arm 258 of the cam lever 250 is connected to a lever 260 fixed to the rocker shaft 244 by a link 262. A second stop finger 264 also arranged to be clamped on the rocker shaft 244 and positioned slightly forward of the stop finger 240 is provided to hold back the line of containers coming in on the conveyor and thereby relieve the safety device, to be described, of any unnecessary pressure. The second stop finger 264 is yieldably mounted in an adjustable bushing 266 which is clamped in a lever 268 attached to the rocker shaft 244. A spring 270 is coiled around the finger 264 between a shoulder 272 on the finger 264 and the bushing 266. A collar 274 fixed to the outer end of the finger 264 is provided to limit the inward movement of the finger, and as a result of this construction the finger is prevented from crushing or breaking a container, should the finger come in contact with the body portion of a container instead of in between two or in front of one container.

In order to prevent a closure from being supplied to the closure applying unit when there are no containers being supplied and conversely to allow a closure to be released when containers are being supplied, a safety device is provided, as best shown in Figs. 7 and 8. This device includes a feeler finger 280 fixed to a vertical shaft

282 mounted in bearings 284 and 286 in a bracket 288. The bracket 288 is loosely mounted on a rocker shaft 290 between a collar 292 and a lever 294 which is clamped to the rocker shaft 290. The shaft 290 fulcrumed in suitable bearing 296 and 298 is actuated by a barrel cam 300 secured to a disc 302 by nuts 303, as seen in Fig. 3. The disc 302 is slidably keyed to the vertical shaft 34. A cam lever 304 fulcrumed on a stud 306 in the machine frame carries a cam roll 308 at one end. A link 310 connects the outer arm 312 of the cam lever 304 to an actuating lever 316 securely fixed to the rocker shaft 290. A spring 318 serves to hold the cam roll 308 against the cam 300.

The feeler finger 280 is normally held in a position at right angles to the conveyor 10 by a spring 320. A lug 322 is provided on the finger 280 which comes in contact with a set screw 324 to adjust the position of the feeler finger. A spring 326 normally urges the loosely mounted lever 288 and the fixed lever 294 toward each other as viewed in Fig. 8. A set screw 328 in the loose lever 288 comes in contact with a guide rail 330 and thereby limits the motion of the lever in this direction. The lower end of the vertical shaft 282 is provided with a latch 332 secured thereto. The lever 294 fixed to the rocker shaft 290, carries a latch block 334. A connection is made between the loose lever 288 and a releasing finger 336 on the chute 156 by a link 338. The link 338 is connected at one end by a connection 340 clamped to a fixed stud in the lever 288. The other end of the link is connected to a lever 342 which is fixed on a fulcrum 344 mounted on the chute 156. The releasing finger 336 is also mounted on the fulcrum 344. With this arrangement it will be seen that when a container comes in contact with the feeler finger 280 it is rocked from its normal position to a position as shown in Fig. 7, and at the same time the latch 332 is thrown into contact with the face of the fixed lever 294. At this time the barrel cam 300 operates to rock the shaft 290 in a clockwise direction viewed from Fig. 8. As the shaft is rocked the latch block 334 on the fixed lever 294 will come in contact with the latch 332 and operate to rock the loose lever 288 with it. This action moves the feeler finger 280 out of the path of the container on the conveyor 10 and allows the container to proceed to the stop finger 240 to be released at the proper time. At the same time a closure is released from the chute 156 to the transfer arm 180 by the releasing finger 336 through the connections described. It will also be apparent that if no container is forthcoming on the conveyor, the feeler finger 280 will not be rocked to the position shown in Fig. 7, and consequently the latch 332 will remain out of the path of the latch block 334. Therefore, when the fixed lever 294 is rocked it will not carry the loose lever with it and no closure will be released from the chute 156.

For the purpose of adjustably raising and lowering the closure applying chuck and its associated mechanism to conform to different sizes and heights of containers, the upper section 42 is arranged to slide vertically on the back of the base 18 and for this purpose a groove 350 is cut in the section 42 to fit over the base 18, as illustrated in Fig. 7. Gibs 351 serve to hold the section 42 in slidable contact with the base 18. In order to raise or lower the section 42 a handle 352 is provided fixed to a shaft 354 which is mounted in a bearing 356 on the section 42. A

bevel gear 358 fixed to the shaft 354 meshes with a bevel gear 360 mounted on the upper end of an adjusting screw 362. The adjusting screw 362 is rotatably mounted in a bearing 364 secured to the upper section 42. The lower or threaded end of the adjusting screw is fitted into a bushing 366 which is secured to a bracket 368 mounted on the base 18. The screw 362 is held from longitudinal displacement in relation 10 to the bearing 364 by a shoulder 370 on one side and by the hub of the bevel gear 360 on the other side. A thrust bearing 372 is provided between the shoulder 370 and the bearing 364. When the handle 352 is turned the adjusting screw 362 is turned in the stationary bushing 366 and causes the upper section 42 to be raised or lowered depending on the direction in which the handle 352 is turned. When the section 42 has been adjusted to suit a certain height of container, clamping screws 374 are tightened down to secure the section 42 to the base 18.

As the vertical shaft 34 is also raised or lowered with the section 42, provision is made to allow the shaft to slide in the lower section, and, 25 as herein shown, an elongated key 376 is fixed in the shaft 34 and the cams and bevel gear 44 are all slidably mounted between bushings 378 and 380 in the base 18. The bushings 378 and 380 are provided with keyways through which 30 the key 376 is allowed to pass and are held from vertical displacement by shoulders 382 on the bushings 378 and 380 which bear against stationary bearings in the base 18. These bushings are rotatably mounted in their respective bearings. This construction allows the vertical shaft 34 to be raised or lowered and at the same time to rotate without displacing any of the parts in the lower section.

While the preferred embodiment of the invention has been herein illustrated and described, it will be understood that the invention may be embodied in other forms within the scope of the following claims.

Having thus described the invention, what is 40 claimed is:

1. In a closure applying machine, in combination, container supporting means, a chuck for

gripping and holding a closure, a vertically movable and rotatable member upon which said chuck is mounted, a stationary supporting member within which said rotatable member is operatively supported to be capable of vertical and rotary movement, and means for imparting both vertical and rotary movement to said rotatable member and the chuck carried thereby including a rotatable vertical shaft, gearing connections between said shaft and said rotatable chuck carrying member, a barrel cam secured to said vertical shaft to rotate therewith provided with a cam path, a cam roll directly connected to said rotatable chuck carrying member and operative within said cam path to effect vertical movement of said rotatable chuck carrying member for the purpose specified, a second cam mounted upon the upper end portion of said vertical shaft, and means cooperating with said cam and said chuck for operating the chuck to cause it to engage and grip the closure. 20

2. In a closure applying machine, in combination, container holding means, closure applying means comprising a chuck, a chuck carrying member upon which said chuck is mounted, 25 stationary means within which said chuck carrying member is mounted to be capable of vertical and rotary movement, said means comprising a housing provided with openings in one surface thereof, means for imparting vertical and 30 rotary movement of the chuck carrying member including a rotatable vertical shaft, a gear secured thereto and extending through one of the openings in said housing, an elongated pinion carried by the chuck carrying member cooperating with said gear, a barrel cam provided with a cam path, also mounted upon said rotatable vertical shaft, a stud carried by the chuck carrying member and extending through the second opening in said housing and provided with a 40 cam roll operative within the cam path in said barrel cam, a second cam upon the upper end of the vertical shaft, and means cooperating with the chuck and the last mentioned cam for opening and closing the chuck, said means including a friction connection. 45

ARTHUR CLARENCE EVERETT.
